CONTACT FEEDING MECHANISM FOR BASE-MAKING MACHINES.

1,151,273.

Specification of Letters Patent. Patented Aug. 24, 1915.

Application filed July 16, 1912. Serial No. 709,662.

To all whom it may concern:

Be it known that I, WILHELM JOST, a subject of the King of Prussia, residing at Berlin, Germany, have invented certain new and useful Improvements in Contact Feeding Mechanism for Base-Making Machines, of which the following is a specification.

My invention relates to machines for making incandescent lamp bases of the type in which an insulating web of glass or similar material holds the contacts and shell in proper relation to one another, and more particularly to improvements by means of which the contacts may be automatically placed in the molds in proper relation to the shell before the molten glass which forms the web is introduced into the shell.

In the manufacture of incandescent lamp bases of this type the metal shell of the base is placed in a suitable mold and one or more contacts, which are afterward connected to the filament of the lamp, are placed in the bottom of the mold out of contact with the shell. Molten glass or other suitable insulating material is then poured into the mold and is pressed firmly in engagement with the shell and with the contacts. One example of a process and machine often used for manufacturing bases of this type is shown in U. S. patent to Swan, 774,708, patented November 8th, 1904. In order that the various operations may be quickly and easily performed the molds are usually mounted on a rotatable carrier which by its rotation brings the molds one after another into position where the contacts are placed in the mold in proper relation to the shell, then into position where the molten glass is introduced, and then into the position where the glass is pressed against the shell and the contacts.

It has been customary to place the metal shell and the contacts in the mold by hand, after which the rotatable holder carries the mold into proper position for the succeeding operations. The shell can be placed in the mold very quickly, but to place the contacts in proper position requires considerable skill and time, particularly in the case of the Swan type of base, in which two elliptical contacts must be placed side by side in the bottom of the mold out of contact with each other and also out of contact with the shell. In the Edison type of base the screw threaded shell forms one contact or terminal, but a circular center contact must be placed in

the bottom of the mold substantially concentric with the shell. To place the contacts in the mold by hand requires so much more time than is required for the other operations that the output of the machine is limited by the speed with which the contacts can be placed in the mold. The time during which the mold is stationary in one position, is too short to enable the operator to insert the contacts in a mold, therefore an eight mold machine, for example, is so arranged that only four molds are in action at any one time, the other four being idle in order that the operator may have time enough to place the contacts.

The object of my invention is to provide means by which the contacts may be automatically placed in the mold in proper relation to the shell; which operates so rapidly that the placing of the contacts in the mold requires no more time than any of the other operations to which the mold is subjected, so that a single stop of the mold is sufficient for the insertion of the contacts; which increases the efficiency and output of the machine; in which the supply of contacts to the machine can easily be maintained; and which is in many particulars hereinafter pointed out an improvement upon base making machine.

In accordance with my invention I automatically feed the contacts from a suitable hopper into the mold where they are held in proper position during the pouring in of the molten glass and the pressing of the glass into shape. In the preferred construction the hopper for the contacts is made in the form of a tube mounted to bring its lower end into registry with each mold as the molds pass, one after the other, beneath the lower end of the tube, each one stopping in alignment with the tube to receive a contact from the tube. The contacts are perforated and are stacked or placed loosely one on top of the other in the tubes. By any suitable means the bottom contact of each row is automatically placed in the particular mold which is then in alignment with the tube. I prefer to use a construction in which, as each comes under the tube containing the contacts, the bottom contact is automatically engaged by a pin which projects from the bottom of the mold and which positions the contact. The bottom contact is then swept eugewise

out of the tube by the movement of the mold toward the next position.

My invention will best be understood in connection with the accompanying drawing, 5 which merely for purposes of illustration shows one of the numerous forms in which my invention may be embodied and in which—

Figure 1 shows a hopper for the contacts 10 in elevation with a part of the movable mold in section; Fig. 2 is a plan view of the mechanism shown in Fig. 1; Fig. 3 is a sectional view along the line 3—3 of Fig. 1 looking down and showing a section of a 15 hopper adapted to hold Swan contacts; Fig. 4 is a similar section of a hopper adapted to hold Edison center contacts; Fig. 5 is a section taken at right angles to the plane of Fig. 1 through the mold and 20 hopper and showing the position of the parts as the mold comes to rest beneath the hopper; Fig. 6 is a similar view showing the bottom of the mold raised into position to engage the lowermost contact; Fig. 7 is 25 a similar view as the mold begins to move to the next position, carrying the lowermost contact with it; and Fig. 8 is a view in perspective of part of the hopper shown in Fig. 1 with some of the Swan contacts in 30 the hopper projecting above the line on which the hopper is broken away in order to show the position of the contacts in the hopper.

As is customary in machines of this kind, 35 the molds are mounted upon the periphery of a rotatable mold holder 1. Each mold is formed of a ring 2 secured to the mold holder and a matrix or movable bottom 3 which is movable vertically in the ring 2. 40 The metal shell of the base is placed in the ring 2 with its lower edge on the matrix 3. The contacts must be placed and held in position on the matrix 3 out of contact with the shell, before the molten glass is poured 45 into the shell. In accordance with my invention the matrix 3 is provided with contact holding means, such as a pin 4 projecting upward from the matrix and serving to hold the contact which is withdrawn 50 from the hopper and then placed in the mold. As the particular form of matrix illustrated in the drawings is designed to be used in the making of Swan bases the matrix 3 is provided with two pins 4 which are 55 small enough to pass through the perforations in the contacts. These pins insure that the contacts will be properly positioned on the matrix and also make openings through the glass web for the leading in 60 wires, which extend from the ends of the lamp filament through the holes in the two contacts when the base is cemented to the lamp bulb.

At the point in the path of the mold 65 holder where the contacts are to be placed

in the mold I mount a hopper which contains the contacts and which is arranged to deliver the contacts to the mold. The form of hopper which I prefer is a tube 5, which, in the particular form shown in the 70 figures, is provided with a longitudinal partition 6 so shaped as to leave two elliptically shaped passages somewhat larger than the elliptical contacts used in Swan bases. Each of the elliptical contacts is 75 perforated at the middle, and in each passage the contacts are superposed in a row with their perforations in alignment. The upper end of the tube 5 is closed by a stopper or cap 7 provided with two depending 80 needles 8 which extend nearly to the lower end of the tube 5 and pass loosely through the holes in the middle of the contacts, so that the contacts are loosely strung upon the needles 8. The bottom of the tube is partly 85 closed by a plate 9 provided with recesses 10 in alignment with the needles 8 and therefore in alignment with the openings in the middle of the contacts. These recesses 10 are smaller than the contacts and consequently the bottom 9 prevents the contacts 90 from falling out of the tube.

In order that the bottom contacts may be automatically delivered in proper position to the mold, I provide means for producing 95 such a relative movement of the tube 5 and matrix 3 that the contact at the bottom of the tube is placed upon the pin 4, and then drawn out of the tube. As best shown in Figs. 5 and 6, the tube 5 has a cut away 100 portion 11 opposite the bottom 9. The cut away portion 11 and the recesses 10 form at the bottom of the hopper an opening which permits the pin 4 to enter the hopper and to pass out through the cut away portion 11. 105 Although the contacts cannot drop out of the tube the lowermost one can be carried edgewise out of the tube through the cut away portion 11, in a direction at right angles to the axis of the tube. The mold 110 holder 1 is carried around step by step by any of the well known mechanisms used for securing a step by step movement. When the mold is stationary and in alignment with the tube 5, as shown in Fig. 5, the matrix 3 115 of the mold is lifted into the position shown in Fig. 6. To lift the matrix 3 I prefer to use a cam, or similar suitable mechanism, which operates in synchronism with the mold holder. I may for example use a vertically movable cam block 3^a, which is normally in the dotted line position shown in Fig. 7, but is raised into the full line position by a rotatable cam 3^b while the mold holder 1 is stationary with the mold 2 in 120 alignment with the hopper. The upward movement of the cam block 3^a raises the matrix 3 into the position shown in Figs. 6 and 7. The cam block is held in the raised position while the mold holder 1 moves to 125 130

ward the next position, and as a result the matrix 3 is maintained in its elevated position during its movement from the position shown in Fig. 6 to the position shown in Fig. 7 and sweeps the contact out of the holder. After the mold holder has moved far enough to carry the matrix 3 slightly beyond the position shown in Fig. 7, the matrix runs off the end of the cam block 3^a, whereupon the cam 3^b is turned a half revolution and permits the cam block 3^a to settle down into the dotted line position ready to repeat the operation when the next mold 2 comes into alinement with the hopper. The proper movements are imparted to the cam 3^b by suitable gearing connecting it with the driving mechanism of the mold holder 1. As the matrix 3 rises the pins 4 pass upward through the recesses 10 in the bottom 9 of the tube 5 and enter the perforations in the bottom contacts 12 in each of the two rows of contacts 13 in the tube 5. The mechanism holds the matrix 3 in the elevated position of Fig. 6 as the mold begins to move toward the left, as shown in Fig. 7. This movement of the mold toward its next position causes the lowermost contacts 12, which are penetrated by the pins 4, to be swept out of the tube edgewise through the cut away portion 11. As the mold moves toward the next position the two contacts 12 are carried along by the pins 4 and are held in proper position upon the bottom 3, as shown in Fig. 7. By the time the mold reaches the next position the mechanism has dropped the matrix or bottom 3 back to the proper position for the subsequent operations of pouring the molten glass into the mold and pressing it into shape. The contacts 12 on the matrix 3 are held in proper position by the pins 4 during these subsequent operations.

When Edison sockets are to be made the bottom of the tube 5 is modified as shown in Fig. 4 to correspond to the circular center contacts used in the Edison sockets. In this case the bottom 14 is provided with a central recess 15 which is in alinement with the perforation at the center of the disk 50 contact of the Edison socket. In this case the cap 7 is provided with only one needle 8 which extends down the center of the tube in alinement with the recess 15. The matrix 3 of the mold is provided with only one pin 4 which is mounted in the center of the matrix so as to position the contact concentric with the shell of the base. As in case of the Swan contacts the matrix 3 is automatically raised until the pin 4 penetrates the center contact at the bottom of the tube, and then the center contact is swept out of the tube by the onward motion of the mold.

In order to facilitate replacing an empty tube with a full one I employ a star shaped holder 16 rotatably mounted upon a rod 17 secured to the machine adjacent the position in which the contacts are placed in the mold.

This star shaped holder 16 is provided at top and bottom with cross arms bored out to receive the tubes 5 which may be set down from above into the cross arms. After a tube is emptied the holder 16 need be rotated only one quarter of a revolution to bring a filled tube into alinement with the mold. To facilitate the rotation of the holder and to insure that it will stop in proper position I provide the bottom of the holder with a notched ring 18 which cooperates with the spring pressed catch 19. When the holder is to be shifted the catch 19 is withdrawn and the holder rotated until the next notch 18 comes into alinement with the catch:

An empty tube may easily be lifted upward out of the holder 16 and replaced by a filled tube, which is inserted in such a manner that the cut away portion 11 of the tube is in the proper direction when the tube is in alinement with the mold to permit the onward movement of the mold to sweep the bottom contact out of the tube through the cut away portion.

My invention may be embodied in many other forms than that described and I therefore do not limit my invention to the precise arrangement disclosed except in so far as it is limited by the scope of the annexed claims.

What I claim as new and desire to secure by Letters Patent of the United States, is:—

1. A machine for making lamp bases comprising a base mold having a pin projecting from the bottom, said mold being mounted to move in a direction at right angles to said pin, a contact holder for holding a perforated contact with its perforation in position to register with the pin on the bottom of said mold and having an opening in alinement with the edge of said contact through which said contact can be swept edgewise out of said holder, and actuating mechanism for producing relative movement of said pin and said holder lengthwise of said pin to thread said contact upon said pin and to then move said mold in a direction at right angles to said pin to sweep said contact through the opening in said holder while threaded on said pin.

2. A machine for making lamp bases comprising a horizontally movable base mold having a pin projecting upwardly from the bottom thereof, a contact holder for holding a perforated contact above said mold in position to bring the perforation in said contact in register with the pin on the bottom of said mold, said holder having a horizontal opening through which the contact can move edgewise out of said holder, and actuating mechanism for producing relative vertical movement between said pin and said

contact to thread said contact upon said pin and to then cause relative horizontal movement of said mold and contact holder while said contact is threaded on said pin and thereby sweep said contact out of said holder.

3. A lamp base machine comprising a horizontally movable base mold provided with a contact holding pin, a hopper for contacts mounted adjacent the path of said mold and constructed to permit the escape of a contact edgewise in the direction of movement of said mold, and actuating mechanism for moving said mold horizontally into alinement with said hopper, then toward said hopper to cause said pin to engage a contact in said hopper, and then continue its horizontal movement to withdraw said contact edgewise from said hopper.

20 4. A base making machine comprising a vertical hopper for perforated contacts constructed to hold contacts in a row one on top of the other and to discharge a contact in a direction perpendicular to the axis of said hopper, and a mold having vertically projecting pins for preventing longitudinal displacement of the contact in said mold, and actuating mechanism for causing said pin and said hopper to first move toward 25 each other along the axis of said mold to bring said pin into the perforation in a contact and then relatively to each other in a direction at right angles to the axis of said hopper to withdraw the contact from said 30 hopper.

5. A base making machine comprising a base mold provided with contact positioning means for preventing displacement of the contacts transversely of the axis of said 40 mold, and a hopper for said contacts constructed to permit said contact positioning means to enter said hopper and engage a contact therein, actuating mechanism for causing said contact positioning means and 45 said hopper to move relatively to each other to first cause said contact positioning means to engage with the contact and then to move transversely out of the axis of said mold and thereby withdraw the contact from said 50 hopper.

6. A base making machine comprising a vertical tubular hopper for perforated contacts for holding the contacts in a row with their perforations in alinement, said hopper 55 being cut away at the bottom to provide an opening for uncovering the edge and the perforation of the lowermost contact, a cover for said hopper, a needle mounted on said cover to extend downward through the 60 perforations of said contacts to leave only a

predetermined number of the lowermost contacts free to be withdrawn through said opening, and a horizontally movable base mold having a vertically movable bottom with a pin for engaging the perforation in 65 the lowermost contact, means for moving said mold past the bottom of said hopper, and means for moving the bottom of said mold to automatically lift said pin into the perforation in the lowermost contact in said 70 hopper during the longitudinal movement of said mold whereby further movement of the mold automatically withdraws the lowermost contact edgewise from the hopper.

7. A base making machine comprising a 75 hopper for containing a plurality of perforated contacts arranged in a row one above the other, said hopper being provided with an opening which permits edgewise withdrawal of the lowermost contact and exposes the perforation in said lowermost contact, a movable base mold having a pin projecting from the bottom to fit loosely in the perforation in said contacts, said hopper and said pin being relatively movable toward each other to automatically bring said pin into the perforation in the lowermost contact, actuating mechanism for moving said pin into operative relation to said lowermost contact and then moving said mold 80 85 toward each other to automatically bring said pin into the perforation in the lowermost contact, actuating mechanism for moving said pin into operative relation to said lowermost contact and then moving said mold 90 95 toward each other to automatically bring said pin into the perforation in the lowermost contact, actuating mechanism for moving said pin into operative relation to said lowermost contact and then moving said mold 100 105 toward each other to automatically bring said pin into the perforation in the lowermost contact, and means for moving said mold toward said hopper and longitudinally of the axis of said row of contacts to bring said pin into the perforation in the lowermost contact and then moving said mold at an 110 angle to the axis of said row to automatically withdraw the lowermost contact from said hopper.

In witness whereof, I have hereunto set my hand this 22 June, 1912.

WILHELM JOST.
